UNITED STATES PATENT OFFICE.

GEORGE E. RICHARDS, OF FISKDALE, MASSACHUSETTS, ASSIGNOR TO THE SNELL MANUFACTURING COMPANY, OF SAME PLACE.

BOX FOR TOOLS.

SPECIFICATION forming part of Letters Patent No. 350,016, dated September 28, 1886.

Application filed March 10, 1886. Serial No. 194,749. (No model.)

To all whom it may concern:

Be it known that I, GEORGE E. RICHARDS, a citizen of the United States, residing at Fiske-
dale, in the county of Worcester and State of
Massachusetts, have invented a new and useful
5 Improvement in Boxes for Holding Tools, of
which the following is a specification.

For shipping boring-bits of various kinds
it is customary, to a certain extent, to arrange
10 them in boxes in assorted sizes, the bits being
fastened by metallic spring-clips which engage
their shanks, so as to hold them within the box
and keep them apart, preventing injurious
contact. This mode requires a spring for
15 every bit, and has been found defective by
reason of the liability of the springs to become
bent, weak, and ineffective, so that it is not
uncommon in opening the box to find the bits
mingled in a confused mass, and consequently
20 more or less injured.

My improvement consists in a box provided
with a bar formed with a number of grooves—
one for each bit-shank—and over this a bar
similarly grooved, so that, the bits being placed
25 in position, the bar is shut down over them
and there held by a spring or springs, fastening
the whole set of bits securely in place.
The box is preferably made double, each part
being provided with the grooved clip-bars
30 above described and the two parts closed to-
gether, by which means a complete set of thir-
teen bits, running in sixteenths from a quar-
ter of an inch to an inch, are contained in a
box of convenient dimensions.

35 In order that the invention may be fully
understood, I will proceed to describe it with
reference to the accompanying drawings, in
which—

Figure I is a perspective view of a box of
40 bits, the box being open, and one of the hinged
clip-bars being elevated. Fig. II is a trans-
verse section of the box closed, the line II II,
Fig. I, indicating the plane of section. Fig.
III illustrates a modification.

45 1 2 represent the two parts of a box, equal

in height and secured together by customary
hinges, 3, and a hook, 4, or other suitable fast-
ening. Within each part of the box is a bridge-
bar, 5, formed with grooves 6, for the recep-
tion of the shanks of the bits B. Over each 50
bridge-bar 5 is a similarly-grooved clip-bar, 7,
connected to the back of the box by hinge 8,
and fastened at its free end by a spring-catch, 9.

In placing the bits in the box their points
are screwed into the end of the box, so as to se-
cure this end and hold them against longitudi-
nal movement. The shanks being set in the
seats prepared for them, and the clip-bar closed
over them, the bits are securely held out of
55 contact with one another, and when the box is
shut are adapted for secure transportation to
any distance without other packing.

Two or more of the bridge-bars 5 and cor-
responding clip-bars, 7, may be provided in
each part of the box, if preferred, the grooves 65
or sockets in one of them being of suitable size
and shape to receive the worm of the bit.

If preferred, the hinges 8 of the clip-bars
may be dispensed with and the bars secured
at both ends by clips 9, as illustrated in Fig. III. 70

The invention is applicable to holding other
tools than boring-bits, and, in fact, to any pur-
pose where a number of tools or like articles
are required to be held apart in parallel posi-
tion for transportation or storage. 75

Having thus described my invention, the
following is what I claim as new therein and
desire to secure by Letters Patent:

1. The combination, with a box, of grooved
bar 5, clip-bar 7, and an automatic means for 80
fastening bar 7 to bar 5.

2. The combination of the two parts 1 2 of
the box, hinged together, grooved bridge-bar
5, hinged clip-bars 7, and spring-catch 9, sub-
stantially as and for the purpose set forth.

GEO. E. RICHARDS.
